RECEPTACLE

Hyman R. Segal, New York, N. Y., assignor to
 Segal Safety Razor Corporation, New York,
 N. Y., a corporation of New York

Application December 13, 1935, Serial No. 54,184

10 Claims. (Cl. 206—16)

This invention relates to a structurally and functionally improved receptacle for properly housing and displaying articles.

While the present invention may be employed in numerous different associations, it is primarily intended for the displaying and housing of articles such as razor blade holders and blades, it being an object of the invention to furnish an article of this character which will, in an improved manner, house a razor or blade holder together with a suitable number of blades and in such manner that these units will not become injured in shipment or in handling of the receptacle.

15 A further object of the invention is that of furnishing a receptacle of this character in which the units contained within the same will be quite accessible when the receptacle is opened, the present device, moreover, lending itself to a proper display of the housed units.

20 A still further object of the invention is that of furnishing a receptacle, the component parts of which may be readily manufactured by well known methods and, if desired, by automatic machinery, these parts being capable of ready assemblage to furnish a unitary device which will operate in a satisfactory manner over long periods of time, and which device may be produced for a nominal figure.

25 With these and other objects in mind, reference is had to the attached sheet of drawings illustrating practical embodiments of the invention, and in which:

Fig. 1 is a perspective view of one form of receptacle embodying the present invention;

30 Fig. 2 is a plan view thereof;

Figs. 3 and 4 are sectional views taken along the lines 3—3 and 4—4, respectively, and in the direction of the arrows as indicated in Fig. 2;

35 Fig. 5 is a perspective view, showing a slightly different form of receptacle from that illustrated in the preceding figures;

Fig. 6 is a fragmentary perspective view of an alternative form of construction; and

40 Fig. 7 is a fragmentary plan view showing a still further form of structure which might be employed.

45 Referring to the drawing, the numeral 10 indicates a receptacle body, which may be formed of any desirable material such as wood, phenolic resin, fiber, or otherwise, and which body may normally be closed by a cover such as 11. As illustrated in Figs. 1 to 4, this cover is connected to the body by rigidly securing to the former an L-shaped plate 12 (of, for example, metal), and

which plate is pivotally connected as at 13 to the body. The arm of the plate is secured to the cover and is of a length such that it equals substantially the depth of the receptacle body. Consequently, when the cover is in closed position, 5 this arm of the plate will constitute, in effect, a rear wall for the receptacle. The plate, moreover, may conveniently be formed with a centrally disposed notch in the outer edge of its second arm, as has been indicated at 14. The 10 purpose of this notch is that of providing a rest for the shank of a razor 15, the head of which may lie to the rear of the free edge of plate 12.

Now with a view to maintaining the cover in closed position and against the probability of 15 accidental shifting with respect to the receptacle body, the latter may support a resilient tongue 16 which tends to normally move outward and which lies adjacent the forward edge of the receptacle body. The inner face of the adjacent 20 cover portion may be notched to receive the end of this tongue, and consequently, as shown in Fig. 3, the tongue will enter this recess to prevent accidental movement of the parts with respect to each other. However, the degree of 25 engagement of these parts will not be such as to prevent a user from overcoming this latching structure. In this connection, it is obvious that by simply grasping the cover with one hand and the receptacle with the other, these parts may be 30 swung from the position shown in Fig. 3 to that illustrated in Fig. 1.

In order to provide compartments for blades as well as with a view to confining the razor or blade holder against undue movement within the 35 receptacle, a spring strip may be employed which is bent to provide a double U-shaped configuration. The area of this strip is normally slightly in excess of the width of the receptacle. However, due to its inherent resiliency, it may be 40 compressed so as to be confined within the receptacle. Thereafter, and upon being released, it will frictionally engage the inner faces of the receptacle body so that accidental dislodgment is precluded. In this connection, it will be 45 observed that the inner faces of the receptacle may be recessed as indicated at 17, to prevent any possibility of a longitudinal shifting of the strip. This member, as illustrated in Figs. 1 to 4, may have relatively broad arm or leg portions 18, 50 which continue in transversely extending base portions 19 and in arms or legs 20 connecting these portions with a central portion 21. The tongue or catch 16 is integral with the strip, and, as illustrated, the depth or width of the outer 55

ends or legs may be such that they extend materially above the edges of the receptacle body.

In this manner it will be obvious that three compartments are furnished. New and/or used

- 5 blades 22 may be disposed within the side compartments and the shank of the razor or holder 15 may reciprocate within and be confined by the central compartment. With the apparatus as shown in Fig. 1, the lid may be swung down-
 10 wardly and the edge of plate 12 will initially cause the entire razor or holder to shift forwardly and thereupon to shift inwardly during the final stages of lid seating. During these movements a sidewise movement of the member 15 will be precluded incident to the rest afforded by the notch 14. Likewise, due to the depth or width of arms 18 the blades will not be able to assume an inclined or tilted position such that the cover will contact the same.
 15 20 In the form of apparatus shown in Fig. 5, the strip may have the upper edges of its outer legs or arms extend upwardly as indicated at 23, to furnish rests which prevent the blades from assuming too inclined a position. Likewise, in lieu 25 of the plate 12, the cover may be directly and hingedly connected, as at 24, to the receptacle body, and the latter is furnished with an integral or fixed rear wall portion. The cover in this instance supports a loop or stirrup 25 of a 30 width such that the head of the razor or holder may be accommodated between the arms of the same. In this manner, the holder is guided so that no improper shifting of the same with respect to the receptacle may occur. However, 35 under all normal circumstances, the lid may be swung so that this implement is either securely housed, or else is brought up to proper displayed position. Coincident with the shipment of the latter, it is obvious that the holder may readily 40 be grasped and removed from the receptacle, or may be readily replaced within the same.

It will be apparent that the plate 12 might be formed integrally with the lid instead of constituting a separate element secured thereto. It 45 will also be apparent that as a consequence of having relatively high walls 18 or extended portions 23, blades may readily be housed within the receptacle without there being any danger that the lid of the latter will strike against the upper 50 edges of the blades and thus destroy their usefulness. The same effect may be achieved by employing the construction shown, for example, in Fig. 6, in which the receptacle body 10 is formed with an inwardly extending flange 26 adjacent its upper side edges. These flanges will serve to 55 maintain any blades in sufficiently upright condition to assure against the lid striking them. In this form of construction the compartment-providing strip 27 may simply terminate in an inwardly extending portion 28. If it is not desired to adopt a structure such as that shown in Fig. 6, a strip of the type shown in Fig. 7 may be employed, in which the body 29 is preferably of the same height or width throughout. The end 60 legs 30 of this body have outwardly extending portions 31 which serve to space the legs 30 from the inner faces of the receptacle body. Consequently, even if a blade assumes an inclined 65 position, and despite the fact that the height of the strip is not great, such inclination cannot result in the upper edges of the blades extending into the path of movement of the lid.

In all forms of construction, it will be apparent that the razor or blade holder will serve to 70 maintain the lid in elevated position after the

latter has been shifted to such position. Additionally, a user will have no difficulty in grasping the holder, for the obvious reason that it has been elevated to a convenient position. Thus, the space accommodating the stem of the holder 5 may be relatively constricted, in that it may never be necessary for the operator to introduce his fingers into such space for the purpose of grasping the holder. This, of course, is also true of the space accommodating the head. 10

Obviously, numerous changes in construction and rearrangement of the parts might be resorted to without departing from the spirit of the invention as defined by the claims.

Having thus described the invention, what is 15 claimed is:

1. A receptacle including a body, a cover, an edged plate rigidly secured to said cover and hingedly connected to said body, the edge of said plate presenting an article receiving notch 20 whereby an article may be disposed within said receptacle body and rest within said notch, said article moving in response to cover and plate movements.

2. A receptacle including a body portion, a 25 cover, an L-shaped plate having one of its arms rigidly secured to said cover and said arm being pivotally connected to said body, the depth of said arm being substantially equal to the depth 30 of said body, and the second arm of said plate providing an article mounting portion, and the free edge of said latter arm being formed with a notch.

3. In combination, a receptacle body, a cover hinged thereto, means for supporting one end of 35 an article disposed within said receptacle body by said cover, and a strip disposed within said receptacle body and providing a compartment for slidingly guiding the opposite end of the article.

4. In combination, a receptacle body, a cover 40 hinged thereto, means for supporting one end of an article disposed within said receptacle body by said cover, and a strip bent to provide a central compartment portion extending within said body and away from said supporting means, 45 said compartment slidingly guiding the opposite end of the article within the receptacle body.

5. In combination, a receptacle body, a cover hinged thereto, means for supporting one end 50 of an article disposed within said receptacle body by said cover, and a strip bent to provide a central compartment portion extending within said body and away from said supporting means, said compartment slidingly guiding the opposite end 55 of the article within the receptacle body, at least one end of said strip being bent to provide a side compartment adjacent said first compartment.

6. In combination, a receptacle body, a cover hinged thereto, means for supporting one end of 60 an article disposed within said receptacle body by said cover, a strip bent to provide a central compartment portion extending within said body and away from said supporting means, said compartment slidingly guiding the opposite end of the article within the receptacle body, at least 65 one end of said strip being bent to provide a side compartment adjacent said first compartment, and the upper edge of said strip adjacent said receptacle body extending materially above the edge of the latter.

7. As an article of manufacture, a strip for association with a receptacle body and including a length of material bent to form a double U-shaped portion, the central part of said material being extended to form a catch. 70

8. As an article of manufacture, a strip bent to provide integrally double U-shaped portions, the depth of the outer legs of such portions being greater than the depth of other portions of said strip.
9. A receptacle including a body, a lid, an L-shaped support hingedly supported by said body and connected to said lid and to hingedly couple the latter to said body, article housing means disposed within said body and including strips extending adjacent the side faces of said body and above the edges thereof, said strips being bent to provide a guideway extending within said body and away from said support and to slidably receive the end of an article, the opposite end of
- 5 said article being mounted by said L-shaped support.
10. A receptacle including a body, a lid, an L-shaped support hingedly supported by said body and connected to said lid and to hingedly couple 5 the latter to said body, article housing means disposed within said body and including strips extending adjacent the side faces of said body, projecting portions forming a part of said strip and extending above the side edges of said body, said 10 strips being bent to provide a guideway extending within said body and away from said support and to slidably receive the end of an article, the opposite end of said article being mounted by said L-shaped support. 15
